OR D 16,858 EX

UNITED STATES PATENT OFFICE.

ARTHUR O. JENNINGS, OF SOUTHPORT, CONNECTICUT.

DESIGN FOR THE ORNAMENTATION OF WATCH-DIALS.

UNITED STATES PATENT OFFICE.

ARTHUR O. JENNINGS, OF SOUTHPORT, CONNECTICUT.

DESIGN FOR THE ORNAMENTATION OF WATCH-DIALS.

SPECIFICATION forming part of Design No. 16,858, dated August 17, 1886.

Application filed June 15, 1886. Serial No. 205,292. Term of patent 14 years.

To all whom it may concern:

Be it known that I, ARTHUR O. JENNINGS, a resident of Southport, in the county of Fairfield and State of Connecticut, have invented and produced a new and original Design for a Watch-Dial, of which the following is a full, clear, and exact description, reference being made to the accompanying photograph.

This invention relates to the new ornamentation of a watch-dial; and it consists in the central ornamentation of the said dial, which shows a rosette resembling a pilot-wheel, as hereinafter shown.

In the accompanying photograph, which represents a face view of a watch-dial having

my design, the letter A represents the watch-case, and B the dial. In the center of this dial is the ornament or rosette C, which resembles a pilot-wheel, showing the spokes, handles, and hub thereof.
